UPRIGHT PIANO

Henry R. Heller, Larchmont, N. Y.

Application August 16, 1935, Serial No. 36,474

6 Claims. (Cl. 84—174)

My present invention relates to improvements in upright pianos. The invention modifies and converts an upright piano so that it has the appearance of a square piano or spinet. The construction not only lightens the appearance of the instrument and emphasizes its horizontal lines at the expense of its vertical lines, but also provides for the proper support of the piano on four legs. The construction enables the legs to be well spaced from the ends of the lower or depending portion of the piano case. Further the appearance is lightened and the tone is improved by narrowing the lower piano case, the sound-board and the piano-back below the key-bed; also by there making the piano case shallower than in the standard upright piano. An improved disappearing fall-board construction is provided in connection with the foregoing cooperative therewith.

With these and other inherent objects and advantages in view, my invention consists in the construction, arrangement and combination of parts hereinafter described and claimed, reference being had to the accompanying drawings which show for the purpose of illustrative disclosure a preferred embodiment of the invention, it being understood however that various changes may be made in practice therein within the scope of the claims without departing from my inventive idea.

In the drawings:

Fig. 1 is a front perspective view of the instrument with the case closed;

Fig. 2 is a front elevation of the same with the upper and lower front panels removed together with the fall-board;

Fig. 3 is a rear elevation of the instrument;

Figs. 4 and 5 are fore and aft sectional views of the instrument, Fig. 5 being a partial duplicate of Fig. 4 with the difference that it shows the fall-board in its up position wherein it is concealed by the upper front panel; and

Fig. 6 is a diagrammatic perspective view of certain parts shown in position for assembly; and

Fig. 7 is a horizontal sectional view partly in plan on the line 7—7 in Fig. 3.

Referring to the drawings, the piano there shown comprises a piano-back 10, a sound-board 12, string-plate 14, piano-action 16, key-bed 18, and key-board 20. The piano-back 10 and sound-board 12 are modified and narrowed below the key-bed 18 to substantially the extent permitted by the string-plate 14 which, as will be seen from Figs. 2 and 3, is much narrower at the bottom than at the top. Thus the piano-

back 10 instead of being rectangular as in the standard upright piano is formed as shown in Figs. 3 and 6 with its lower part much narrower than its upper part, the ends 10a of its lower part being abruptly connected with the ends 10b of the upper part by means of the horizontal shoulders 10c. Preferably the ends 10a of the lower part are concaved inwardly as shown.

The width and shape of the lower part of the sound-board 12 conform to the piano-back 10 which is another radical difference from the standard upright-piano wherein the sound-board is rectangular like the piano-back and extends for substantially the full-length of the piano both above and below the key-bed.

The piano-case comprehensively designated 22 is also narrowed below the key-bed and has or may have inwardly concaved ends 22a to conform with the piano-back.

The string-plate, sound-board and piano-back 20 are combined and secured together in accordance with standard upright piano construction.

The shoulders 10c of the piano-back rest upon end-beams 24 which in turn are supported by piano legs 26 so that preferably the bottom 22b of the piano-case is clear of the floor as best shown in Figs. 2 and 3. The cheeks 22c of the piano case are glued or otherwise suitably secured to the upper end portions of the piano-back in the position shown in Fig. 3. These 30 cheeks also rest upon the end-beams 24 as shown in Fig. 3. The ends of the key-bed 18 also rest upon said end-beams. Fig. 6 shows how the key-bed has each of its ends formed to be receivable into a recess 22d in the adjacent cheek-piece 35 22c. Screws 28 (Fig. 6) secure the cheek pieces to the key-bed. Other screws 30 secure the end-beams to the piano-back shoulders, and to the cheek pieces, Figs. 3 and 6.

The piano-legs 26 are preferably directly secured to the end-beams 24, so that in case a leg has to be replaced, it is easy to unscrew the end-beam carrying the broken leg and replace it with another with legs intact. This construction locates the piano legs, two on a side, well spaced 45 laterally from the lower or depending portion of the piano case and gives a spinet appearance to the upright piano.

The key-board 20 and the piano-action 16 are supported in proper operating position relatively 50 to the strings and other parts as in standard upright-piano construction.

The cheeks 22c of the piano case at the ends of the key-board are or may be higher than in the standard upright and preferably extend up

to about the level of the hammer-rail 32, but may be higher or lower than that, depending upon the effect and appearance desired. These cheeks 22c as shown in Fig. 1 preferably extend at the same height clear to the back of the case. The upper ends 22e of the piano case have a fore and aft dimension at the top which is or may be substantially the same as the corresponding dimension in the standard upright case. The forward edges 22f of these ends preferably incline downwardly and forwardly to the cheeks 22c as shown in Figs. 1, 6, etc. 34 is or may be a standard upright piano-lid hinged at its back. The usual key-slip 36 is secured between the cheeks 22c at the front ends of the keys.

The upper front panel 38 (Figs. 1, 4 and 5) of the piano case is hinged at its upper edge between the ends of the case, so that it can be swung forwardly and upwardly to enable the fall-board to be received and concealed behind it, when the keyboard is exposed for playing. The fall board as best shown in Figs. 4 and 5 consists of a vertical panel 40a and a horizontal panel 40b hinged together at 40c. The horizontal panel 40b at its back edge 40d is pivotally supported between the cheek-pieces. The hinge 40c between the panels permits them to be collapsed against each other. They can then be swung upwardly and rearwardly about the pivot 40d into the position shown in Fig. 5 wherein they rest against a projection or stop 42. To permit the foregoing, the front panel 38 is temporarily swung outwardly and upwardly as shown in Fig. 5. When returned to its normal position, this panel 38 effectively conceals the fall-board. The front panel 38 is or may be provided with a foot-portion 38a to form a music-rack or desk.

The piano-back, sound-board and piano-case are not only much narrower in lateral expanse below the key-bed than in the standard upright, but also the piano-case is there much shallower in fore and aft direction than in the standard upright. This is best seen in the end elevation Fig. 4 where the fore and aft dimension or depth of the lower part of the case is seen to be considerably less than the upper part of the case at the top.

The pedals are operatively supported on a lyre 44 as in a grand piano which is secured to the key-bed in front of the lower front panel 46 (Fig. 1).

The effect of the entire construction as compared with the standard upright is to improve both the tone and the appearance.

There is a marked improvement in tone in the instrument as compared with the standard upright having the same sized string-plate. The tone is decidedly fuller and more sustained. This

is accounted for by the narrower sound-board and piano-back construction below the key-bed. Also the narrower and shallower lower piano-case probably contributes to the improved tone by reinforcing to the tone. Also the fact that the bottom of the piano case and the contained construction are preferably supported free of the floor is believed to improve the tone.

The whole appearance is lightened and changed from the wardrobe appearance of an upright-piano to the appearance of a spinet. This is accomplished by the marked narrowing of the case and other parts below the key-bed with resulting accentuation of the horizontally projecting ends of the key-bed and positioning of the piano legs, two at each end, spaced well away from the ends 22a of the narrowed piano case.

What I claim is:

1. In combination, a piano-back, sound-board, string-plate, key-bed, key-board, piano-action and piano-case combined as in a standard upright piano but wherein the piano-back, sound-board and piano-case are narrowed below the key-bed to substantially the extent permitted by the string-plate, the piano-back having horizontal shoulders connecting the narrowed lower portion thereof with its wider upper portion; end-beams whereon said shoulders rest and are secured; and piano-legs secured under the front and rear ends of each beam.

2. The combination claimed in claim 1 further characterized by the ends of the narrowed lower part of the piano-case, piano-back and sound-board being inwardly concaved.

3. The combination claimed in claim 1, further characterized by the said lower piano-case being shallow from front to rear and only deep enough substantially to take in the piano-back, sound-board and string-plate.

4. The combination claimed in claim 1, further characterized by said legs being long enough to support the piano case and contained parts off the floor.

5. The combination claimed in claim 1, further characterized by having cheeks at the ends of the key-board united with end portions of the piano-case above said cheeks, the ends of the key-bed being supported on the aforesaid end-beams and being united with said cheeks.

6. The combination claimed in claim 1, further characterized by having cheeks at the ends of the key-board united with end portions of the piano-case above said cheeks, the ends of the key-bed being supported on the aforesaid end-beams and being entered into recesses formed in said cheeks and being united with said cheeks.

HENRY R. HELLER.
